UNITED STATES PATENT OFFICE.

ELMER D. STONE, OF FRAMINGHAM, MASSACHUSETTS.

LAST.

Application filed July 21, 1925. Serial No. 45,096.

To all whom it may concern:

Be it known that I, ELMER D. STONE, a citizen of the United States of America, and a resident of Framingham, in the county of 5 Middlesex, State of Massachusetts, have invented certain new and useful Improvements in Lasts, of which the following is a specification.

This invention relates to lasts and particularly to lasts used in the manufacture of 10 rubber boots and shoes, the object of the invention being to protect the bottom edges of such lasts, to prevent them from being nicked and otherwise injured when these 15 lasts are thrown about in a factory.

This object is attained by the means illustrated in the accompanying drawing.

For the purpose of illustrating the invention, one preferred form thereof is illustrated in the drawings, this form having been found to give satisfactory and reliable results, although it is to be understood that the various instrumentalities of which the invention consists can be variously arranged 25 and organized, and the invention is not limited to the precise arrangement and organization of these instrumentalities as herein shown and described except as required by the scope of the appended claims.

30 Of the drawings:

Figure 1 represents an inverted plan of a last embodying the principles of the present invention.

Figure 2 represents a side elevation of 35 same.

Figure 3 represents a transverse section of same on line 3, 3, on Fig. 1, and

Figure 4 represents a similar section after the last has swelled.

40 Similar characters indicate like parts throughout the several figures of the drawings.

In the drawings 10 is a last adapted for use in the manufacture of rubber boots and 45 shoes, the lower end of which is provided with sockets 11 to receive positioning pins of any suitable machine on which it is desired to mount said last.

These lasts are usually made of wood and 50 in the manufacture of rubber boots and shoes thereon, they become subjected to moisture which causes them to swell and heat which causes them to again shrink.

This continually changing of conditions 55 causes the wood of the last to become very brittle and when the lasts are thrown about

in the factory the edges become nicked and broken to such an extent as to make them unfit for further use, consequently it is quite essential that the bottom of the last should be given some protection, particularly at the edges to prevent injury thereto.

A metal plate covering the entire bottom surface would be unsatisfactory for it would not permit the widening and narrowing of the last during the swelling and shrinking of the wood and the outer edge of such a plate could not be maintained in register with the outer edge of the last under these different conditions.

70 It is quite essential that the edge of any reinforcing plate should coincide with the edge of the last at all times.

In order to accomplish this result depressions 12 are formed at the opposite sides of 75 the bottom of the heel 13 and fore part 14, these depressions being separated by the upwardly extending projections 15 extending lengthwise of the last.

In each of these depressions 12 is positioned a reinforcing strip or plate 16 of metal or other tough material, said strips or plates 16 being secured in position by the members 17 at points adjacent the outer edges of said plates 16.

80 These plates are secured to the last when shrunk to its narrowest condition, as indicated in Fig. 3, and at this time the plate 16 will fill the entire depression 12 with the outer edges of the plates 16 registering with the outer edges of the heel 13 and fore part 90 14 of the last, and the inner edges of said plates abutting the opposite vertical walls of the projections 15.

When under varying degrees of temperature the last commences to swell the plates 16 will move away from each other leaving the spaces 18 as shown in Fig. 4.

95 This Fig. 4 is somewhat exaggerated in order to more clearly illustrate the fact that no matter how much the last swells the outer edges of the plate 16 are still in register with the edges of the heel and forepart of the last.

100 As a consequence, notwithstanding the varying conditions of the last, the bottom edges thereof will be well protected at all times.

When the last again shrinks the plates 16 110 will move toward each other until their inner edges again abut the walls of the projections 15.

2
By the use of these protecting plates 16 the lasts are serviceable for long periods and the manufacturer is saved the expense of replacing them.

5 It is believed that the operation and many advantages of the invention will be understood without further description.

Having thus described my invention, I claim—

10 1. A rubber shoe last having separated metal plates inserted into the opposite sides of the bottom thereof with their outer edges registering with the outer edges of said last, said plates being secured to the bottom face 15 of the last only at points closely adjacent the edges thereof.

2. A rubber shoe last having separated metal plates inserted into the opposite sides of the bottom of the heel and forepart thereof 20 with their outer edges registering with the outer edges of said heel and forepart, said plates being secured to the bottom face of the last at points adjacent the outer edges thereof, the inner portions of said plates 25 being free to move relatively to the face of the last during the swelling and shrinking thereof.

3. A rubber shoe last having depressions in the opposite sides of its bottom and extending to the edges thereof, and a separate metal plate positioned in each depression and secured to said last only at the outer edges thereof, said plates having their outer edges registering with the edges of the last and their bottom faces in the same plane with the bottom of the last.

4. A rubber shoe last having separate metal protecting strips secured to its bottom at the opposite edges thereof and movable toward and from each other during the shrinking and swelling of said last.

5. A rubber shoe last having flat faced depressions in the opposite sides of its bottom and extending to the edges thereof, and a separate flat metal plate positioned in each depression and secured by screws to said last closely adjacent its outer edges, said plates having their outer edges registering with the edges of the last with their inner portions free to move relatively to the bottom face of the last and parallel thereto.

Signed by me at 746 Old South Bldg., Boston, Mass., this 20th day of July, 1925.

ELMER D. STONE.
